ELECTRIC LAMP SOCKET FOR ELONGATED
TUBULAR LAMPSTrygve Wold, Georgetown, Ontario, Canada, as-
signor to Smith & Stone Limited, Georgetown,
Ontario, CanadaApplication November 21, 1949, Serial No. 128,516
In Canada September 19, 1947

1 Claim. (Cl. 173—328)

1
This invention relates to sockets for tubular electric lamps, such as fluorescent lamps, having a plurality of aligned contact pins at each end.

Sockets of this type are positioned at each end of a fixture and each socket has a foot of a standard shape which fits into the underside of the fixture, suspending the socket's lamp opening below the foot and allowing the lamp to be inserted or removed by a person standing beneath the fixture.

The sockets which have been in common use, for example in tubular fluorescent lamp fixtures, consist of an insulating base having a lamp opening in one face and resilient contact members. The lamp opening has a neck-like portion extending to an edge and adapted to pass contact pins longitudinally to the opening proper which is adapted to permit rotation of the lamp and thus of the contact pins. The resilient contacts are formed with V sections and spaced one at each side of the lamp opening so that when the lamp is rotated (usually a quarter revolution) the pins become seated in the bottom of the V sections.

The fluorescent lamps which these sockets are used to support within a fixture, are about three feet long and of considerable weight. Since the fixtures are usually supported near the ceiling and are open at the bottom, it is necessary to insert the tube from the bottom edge of the socket and then to rotate it a quarter revolution within the opening in the socket's base to bring the pins into the V section of the contacts. When inserting these lamps it has been found to be very difficult to position them properly in the bottom of the V sections since the weight of the lamp makes it difficult, if not impossible, to feel the contact pins become seated. Often a lamp is left without all pins seated because the lamp has been turned more or less than one quarter revolution, and it subsequently falls from the fixture exposing people in the vicinity to flying particles of glass as the lamp explodes on the floor.

According to the present invention, the disadvantages of the prior art have been avoided by providing a lamp socket for electric lamps having a plurality of aligned contact pins which comprises an insulating base, an opening in one face of the base having a neck portion extending to an edge of the base and adapted to pass aligned contact pins longitudinally, and an enlarged portion adapted to permit rotation of the lamp base having aligned pins thereon, resilient contact members spaced within the opening and adapted to engage the contact pins when the lamp is ro-

tated and means adapted positively to stop rotation of the lamp before the pins return to alignment with the neck portion of the opening.

When inserting the lamp into a fixture having 5 sockets according to the present invention, the lamp is raised up into the fixture until its contact pins are within the openings in the sockets, and then it is rotated until the pins contact the means adapted positively to stop rotation. These 10 means may consist of a projection on at least one of the contact members.

The invention will now be described by reference to the accompanying drawings which illustrate an embodiment of it and in which:

15 Figure 1 is a view of a tubular lamp held by two sockets of the type referred to.

Figure 2 is a front view of a socket according to the invention.

Figure 3 is a rear view.

20 Figure 4 is an enlarged cross section on the line 4—4 of Figure 2.

Figure 5 is an enlarged view of part of the socket as shown in Figure 2.

A socket 10 according to the invention consists 25 of a conventional insulating base 11 of plastic material moulded with a circular opening 12 in the front face thereof and a narrow neck 14 extending to an edge of the base 11. A foot 15 is of the standard shape for fitting into a light fixture. Resilient contact members 16 are housed in the usual way in a cavity 17 at the rear of the base 11, which cavity 17 joins with the opening 12 allowing the contact members 16 to pass through the opening 12 at either side of a guide post 18. Each of the contact members 16 has a 30 broad U-shaped section 19 formed in it opposite the guide post 18, and a projection 20 is formed at the centre of each U section 19 and extends into a slot 21 in either side of the guide post 18. The guide post 18 has a slot 22 of approximately 35 the same width as the neck 14. Screws 23, within the foot 15, thread into the contact members 16 for attachment to the wiring of the fixture, and a removable insulating strip 27 covers the back 40 of the cavity 17.

45 The sockets 10 are held in the position shown in Figure 1 when mounted on a fixture (not shown) and lamp 24 is supported between them. A plurality of aligned contact pins 25 is provided 50 at each end 26 of the lamp 24 and the lamp is put into the fixture by inserting the aligned pins longitudinally into the neck 14 of each socket and pushing the lamp 24 up into the fixture until the first of the contact pins 25 has passed through 55 the slot, and the pins 25 straddle the guide post

18. The lamp 24 is then rotated in either direction causing the contact pins to enter the U-shaped sections 19 and engage the projections 20 which positively stop the aligned pins 25 rotating far enough to be again aligned with slot 22. In the embodiment illustrated the projections 20 prevent more than one quarter revolution in either direction.

When rotation of the lamp is stopped by the contact pins 25 engaging the projections 20, the person inserting the lamp knows that the proper contact is made and that the lamp may be safely left in the fixture without danger of it subsequently falling therefrom.

What I claim as my invention is:

A socket for electric lamps having a plurality of aligned contact pins, comprising an insulating base, an opening in one face of the base having a neck portion extending to an edge of the base and adapted to pass a plurality of aligned contact pins longitudinally, a guide post having slots therein and an enlarged portion adapted to per-

mit rotation of the lamp, resilient contact members spaced within the opening and adapted to engage the contact pins when the lamp is rotated, each of said contact members having a broad, U-shaped section formed in it opposite the said guide post, and means centrally disposed on each of said U-shaped sections extending into the said slots in the guide post adapted positively to stop rotation of the lamp before the said pins return to alignment with the neck portion of the opening.
